UNITED STATES PATENT OFFICE.

WILLIAM R. DAUGHERTY, OF BIRMINGHAM, ALABAMA.

COMBINED COVER AND FILING-CABINET FOR MUSIC-RECORD ROLLS AND THE LIKE.

1,252,247.

Specification of Letters Patent.

Patented Jan. 1, 1918.

Application filed October 15, 1915. Serial No. 56,095.

To all whom it may concern:

Be it known that I, WILLIAM R. DAUGHERTY, a citizen of the United States, residing at Birmingham, in the county of Jefferson 5 and State of Alabama, have invented new and useful Improvements in Combined Covers and Filing-Cabinets for Music-Record Rolls and the like, of which the following is a specification.

10 This invention relates to an improved filing cabinet for player piano music rolls, automatic organ rolls, rolled maps, blue prints, hospital charts and other similar rolled devices or records. At the present time any 15 available filing cabinet for player piano rolls, for instance, is an expensive adjunct to the player piano, and, in addition, is inconvenient for the player operator to gain access to the rolls therein without leaving 20 his seat, and, moreover, the labels on the rolls or inclosures for the latter cannot be read without difficulty owing to the distance that the usual form of filing cabinet is located from the player piano. The main 25 object of the present invention is to provide a very convenient and economical filing case which is particularly adapted to protect player piano and other analogous rolls and involving a readily observable index, the im- 30 proved filing case being within easy reach- ing distance of the arm of the operator or player and having labels easily readable without requiring the operator to leave his seat or to lean or turn around. In the em- 35 bodiment of the invention for use on player pianos and like instruments the particular object in view is to dispose the filing cabinet on the top portion of the player piano or like instrument so that all of the rolls may 40 be readily accessible to the operator, and also to so arrange the labels that any roll desired may be quickly obtained from the cabinet.

The improved cabinet essentially consists 45 of a plurality or series of flexibly connected, joined or linked inclosures or boxes of any suitable type and having such dimensions that the rolls may be readily inserted there- 50 in and withdrawn therefrom, and as a tex- tile cover known as a scarf is invariably furnished by piano dealers with each piano or player piano sold by them advantage of this particular cover or scarf is taken as a fundamental feature for the construction and ar- 55 rangement of the cabinet; and in one of the preferred forms of the invention the series

of inclosures or boxes is secured in regular order to the under portion of the cover or scarf and a part of the latter is designed to serve as a front overhang or curtain so as 60 to conceal the inclosures or boxes as well as protect their contents. It is also proposed to form the cover exclusively of a series of ornamental boxes flexibly connected by any suitable means, and when so joined the se- 65 ries of boxes will serve every purpose of the usual textile cover and may be orna- mented and provided with closing flaps for the ends of the boxes or inclosures, and at the same time this form of cover involving 70 the series of boxes or inclosures may be uti- lized as receptive means for the rolls of player music or for other purposes to which the invention may be applicable. Many 75 modifications in the manner of connecting 80 the boxes or inclosures may be adopted and several variations will be hereinafter speci- fied, but in all the forms the essential fea- tures of the invention are embodied and re- side in the economy attained relatively to 85 all forms of cabinet furniture which are ex- pensive and heavy besides being costly to pack, haul and ship. In accordance with 90 my invention the cost of attaching a few reinforced pasteboard or other boxes, either 95 to each other or to the cover or scarf, is a trifle as compared to the expense of an ordi- nary cabinet, and the whole outfit including the filing cabinet and player piano or other analogous instrument may be shipped in 100 the same box at a minimum expense in the cost of transportation and without extra trouble of unpacking when it is desired to set up the player piano or other instrument and the improved cabinet for use.

The invention also consists in the details of construction and arrangement of the se- 105 veral parts which will be more fully herein- after described and claimed.

In the drawings:

Figure 1 is a front elevation of a portion of a player piano showing the improved combined cover and filing cabinet applied thereto.

Fig. 2 is an elevation of a portion of the 105 player piano similar to Fig. 1 and also of a part of the filing cabinet and cover showing one of the flaps of the latter raised and ex- posing one of the receptacles for the record roll that is inserted therein.

Fig. 3 is an end elevation of a portion of 110 the player piano showing the improved

combined cover and filing cabinet thereon in sectional elevation.

Fig. 4 is a detail perspective view of the combined cover and filing cabinet shown 5 folded to reduce the same to compact form for transportation.

Fig. 5 is an end elevation of the improved combined cover and receptacles showing the latter in rolled condition for transportation.

10 Fig. 6 is a front elevation of a portion of a player piano showing the improved cover and cabinet thereon and embodying a modification, the curtain portion of the cover being partially raised to expose the receptacles 15 or inclosures for the rolls.

Fig. 7 is a longitudinal vertical section taken in the plane of the line 7—7, Fig. 6, and showing one of the receptacles or inclosures and cover with the label attached 20 to the front of the inclosure or receptacle the cover being removed.

Fig. 8 is a view similar to Fig. 7 showing the textile cover removed and the label down over the front end of the inclosure or 25 receptacle.

Fig. 9 is a front elevation of the device as shown by Fig. 8.

Fig. 10 is a view similar to Fig. 7 and showing a further modification wherein the 30 label is attached to the textile cover instead of to the top front portion of the inclosure or receptacle.

Fig. 11 is a front elevation of a portion of a piano player with the improved combined cover and filing cabinet thereon and showing a further modification consisting of the application of the labels to the outer side of the curtain portion of the cover.

Fig. 12 is a front elevation of a portion 40 of a player piano showing the upper part in longitudinal section and also illustrating the combined cover and filing cabinet thereon and also shown in section and involving a still further modification consisting in 45 utilizing the receptacles or inclosures solely as the cover without the textile cover portion in connection therewith, the receptacles or inclosures in this instance being flexibly united by connecting links, cords or analogous devices.

For the purpose of practical demonstration of the invention the combined cover and filing cabinet is shown applied in the accompanying drawings to a player piano, but 55 it will be understood that the invention may be used in connection with any other musical instrument or for the purpose of storing in indexed or labeled form any rolled records or devices to which the improved device may be adapted. Therefore, it is intended by the subsequent description to disclose only one use of the improvement, and the modifications which will be hereinafter referred to are intended to show that the 60 invention is not limited to any specific form

or precise organization, and other changes in the details of construction may be adopted at will and come fully within the scope of the invention.

Referring particularly to Figs. 1 to 5 inclusive, the numeral 5 designates a player piano of any preferred type on which the combined filing cabinet or cover and inclosures or receptacles for the record rolls of the piano are applied. The combined filing 70 cabinet or cover and inclosures or receptacles comprises a textile fabric cover 6 of any suitable ornamental character provided with drop ends 7 and a front curtain or shield portion 8, the curtain or shield portion being regularly formed with a plurality of flaps 9 by severing the said curtain at intervals, as at 10. The inclosures or receptacles consist of elongated boxes 11 closed at their rear ends 12 and fully open at their front 75 ends 13. These boxes 11 are of such length as to receive the standard music rolls 14 for player pianos and other instruments and have their top portions suitably secured to the under side of the textile fabric cover 6 80 at regular intervals and by means of which the said boxes are flexibly connected so that they may be folded into compact form, as shown by Fig. 4, or rolled, as shown by Fig. 5, for convenience in packing and 85 transporting the improved combined cover and filing cabinet with the instrument on which it is to be used. When thus inclosed 90 for shipment with the instrument, the device may also serve as an indexed packing 100 case for the record rolls which are being shipped with the instrument. The front open end 13 of each box 11 is directly in rear of one of the flaps 9, each flap covering or closing the front open end of a box, and 105 on the outer side of the flaps are labels 15 on which are written or printed or otherwise applied the names of the musical compositions of the rolls disposed in the corresponding boxes 11. It is proposed to apply any 110 suitable information on the labels in addition to the names of the musical records, and it will be seen that the records as held in the improved filing cabinet and also the 115 labels will be readily accessible and observable to the operator of the player piano, and after one record roll has been used it may be stored in its proper box or receptacle and another record roll easily obtained and mounted in position in the player piano 120 without requiring the operator to be subjected to the least inconvenience or to leave his seat at the instrument. The under sides of the boxes 11 are also provided with pads 16 of any suitable material, said pads bearing upon the top portion of the player piano 125 to prevent the boxes from scratching the player piano top. These pads 16 also uniformly raise the lower sides of the boxes 11 130 sufficiently to clear the top portion of the

player piano and especially the hinge 17 usually located at the top portion of the piano, as shown by Fig. 3.

When the improved cover and filing cabinet net are folded as shown by Fig. 4, or rolled as shown by Fig. 5, they may be readily inserted in the box or casing used in transporting and shipping the player piano and thereby avoid the use of an independent shipping inclosure for the improved device. It will also be understood that the improved device may be furnished as a part of the equipment of the player piano on which it is adapted to be used and thereby serve as a commercial inducement in the purchase of the piano.

Essentially the same structure is shown by Figs. 6 to 9, inclusive, but the cover 6 in this instance is provided with a front curtain or shield member 18 which is intact throughout its entire length or is not formed with the flaps 9 as shown by Figs. 1 and 2. In Figs. 6 to 9, inclusive, the front top portions of the boxes 11 have flaps 19 secured thereto to depend partially over the front open ends 13 of said boxes, these flaps 19 carrying labels or label holders 20 of any preferred form. When the record rolls 14 are withdrawn from the boxes 11 in the structure disclosed by Figs. 6 to 9, inclusive, the boxes have their front open ends 13 cleared by first throwing the curtain or shield member 18 backwardly over the body of the textile fabric cover 6, as shown by Fig. 7, and the withdrawal of the rolls 14 causes the label holders 20 and flaps 19 to be elevated to clear the said rolls. When the rolls 14 are again inserted in the boxes 11 the label holders and their flaps may be manually raised to clear the open ends 13 of the boxes 11.

In the form of the device shown by Fig. 10, flaps 21 are secured to the textile fabric cover 6 and carry label holders 22, but in other respects the organization illustrated by Fig. 10 is the same as that shown by Figs. 6 to 9, inclusive. The boxes 11, shown by Figs. 6 to 10, inclusive, are secured to the textile fabric cover 6 in the same manner as the organization shown by Figs. 1 to 5, inclusive.

In the form of the improvement shown by Fig. 11 the boxes 11 are secured to the textile fabric cover 6 in the same manner as the structures shown by Figs 1 to 10, inclusive, and in this instance the curtain or shield member 18 has labels 23 secured to the outer side thereof at intervals to correspond with the records in the boxes directly in rear of the portions of the curtain carrying the labels. In this latter construction it is proposed to slit the curtain 18 at intervals, as at 24, and then draw a long strip 25 of celluloid or other transparent material through the slits and thereby form a series of shields

behind which label cards may be placed and easily read through the celluloid or other transparent material. The curtain as shown by Fig. 11 may be raised high enough at any point to permit the withdrawal of a roll 70 from its box or receptacle.

If it be desired to employ a series of ornamental boxes 26 without a textile cover, said adaptation of the invention may be readily accomplished within the scope of the invention by connecting the boxes by flexible links or straps 27, as shown by Fig. 12, the contiguity of the boxes in this structure serving the combined purpose of a filing cabinet for the rolls and a cover for the instrument. 80 The pendent ends 28 of the form of the device as shown by Fig. 12 will also comprise boxes 26 of smaller dimensions than the main group of boxes for the reception of rolls of small diameter. These end or 85 pendent boxes or receptacles may also be applied in connection with the textile cover as heretofore disclosed, it being obvious that such additional boxes would be but a continuation of the boxes over the ends 7 of 90 the cover as shown by Figs. 1 and 2 as well as by Figs. 6 and 11.

In all the forms of the device as hereinbefore explained the same principle of invention is involved, that is, a series of inclosures 95 or receptacles flexibly connected in series or in groups for the reception of roll records, and the open ends of the boxes, as shown by Fig. 12, will be closed by suitable flaps if desired, or remain open, as may be best 100 adapted to the purpose for which the improved device is to be used. In all the forms of the device shown it will be seen that all of the boxes are arranged in connected sequence, or side by side, and in each of the 105 forms also the boxes may be folded as indicated by Fig. 4, rolled as shown by Fig. 5, or laid flat or in open condition as shown by Figs. 1, 2, 6, 11 and 12. It will also be understood that the boxes may be constructed 110 of any material adapted for the purpose and the proportions and dimensions thereof may be varied at will.

What is claimed is:

1. In a device of the class specified, a plurality of receptacles for holding roll records for use on top of a player piano or other device, and a cover for the piano or other device having the receptacles secured thereto to prevent the receptacles from being 115 disarranged.

2. A music roll holding cabinet comprising a plurality of receptacles arranged side by side in a horizontal plane, each receptacle having one end thereof open, in combination 120 with a textile sheet secured to the series of receptacles along the upper face of the latter, said sheet being adapted to cover the open ends of the music holding receptacles to normally hide said music roll holding cabinet 125 130

whereby a neat and pleasing appearance is presented.

3. In a music roll cabinet, a textile cover for player piano or other analogous instruments, and a series of longitudinally alined music roll holding receptacles having their open ends adjacent to each other, the textile cover being disposed on the receptacles and provided with a curtain portion normally 10 depending over and shielding the open ends of the receptacles and carrying labels adjacent to the open ends of the receptacles and disclosing the character and means of the rolls in the several receptacles.
- 15 4. A music roll holding cabinet comprising a plurality of receptacles arranged side by side, each of the receptacles having one end open, in combination with a textile sheet secured to the series of receptacles 20 along the upper face of the latter, and a plurality of flaps integral with the textile sheet and normally overlying the open ends of the receptacles, one face of each flap serving as a title carrying means to indicate the name 25 of each music roll.
5. A music roll holding cabinet comprising a plurality of receptacles arranged side by side, each of the receptacles having one end open, in combination with a sheet of 30 material secured to the series of receptacles along the upper face of the latter and having a curtain portion normally overlying the open ends of the receptacles, the curtain portion being slit at intervals, a strip of trans- 35 parent material inserted through the slits of the curtain portion and regularly exposed exteriorly to form a series of transparent shields, and label cards disposed in rear of the exteriorly exposed portions of the trans- 40 parent strip and in front of the several receptacles.
6. In a music roll holding cabinet of the class specified, a series of longitudinally

alined music roll holding receptacles having open ends adjacent to each other and all disposed at the front of the series of receptacles, the rear ends of the receptacles being closed, and means for flexibly connecting the series of receptacles and whereby a cover for a piano top is provided embodying the said receptacles with their open ends all located at the front within easy reaching distance of a player for the withdrawal of music rolls from an insertion of said rolls in said receptacles. 45 50 55

7. In a music roll holding cabinet for the top of a player piano or analogous device, a single line of receptacles arranged side by side, each receptacle having one end open and all of the open ends thereof disposed at 60 the front, and means for connecting the receptacles and permitting the latter to have opening and closing movements at the side portions relatively to each other whereby the receptacles may be spirally rolled to reduce 65 them to compact form.

8. In a music roll holding cabinet of the class specified, a plurality of receptacles arranged side by side in a horizontal plane, each receptacle having one end thereof open 70 and a bottom pad secured thereto to engage the support on which the cabinet is applied, all of the open ends of the receptacles being at the front of the plurality of receptacles, and means for movably connecting the receptacles to permit the side portions of the latter to move toward and from each other when folded or to conform to the surface on which the cabinet as a whole is applied. 75

In testimony whereof I have hereunto set 80 my hand in presence of two subscribing witnesses.

WILLIAM R. DAUGHTRY.
